(57) **CLAIM**

The new, original and ornamental design for an electrical connector, as shown.

DESCRIPTION

FIG. 1 is a front view of the electrical connector, showing my new design;

FIG. 2 is a rear view thereof;

FIG. 3 is a top plan view thereof;

FIG. 4 is a bottom plan view thereof;

FIG. 5 is a left side view thereof, the right side view being a mirror image thereof;

FIG. 6 is a top side perspective view thereof; and,
FIG. 7 is a bottom side perspective view thereof.

In the figure drawings, the even-broken line shown in the figure drawings is included for the purpose of illustrating environment and forms no part of the claimed design. The dash-dot-dot line represents the boundary line of the claimed design.
